UNITED STATES PATENT OFFICE.

FRANCIS M. BROWN, OF GREENFIELD, IOWA.

HEN'S NEST.

SPECIFICATION forming part of Letters Patent No. 311,467, dated February 3, 1885.

Application filed August 11, 1882. (Model.)

To all whom it may concern:

Be it known that I, FRANCIS M. BROWN, a citizen of the United States, residing at Greenfield, in the county of Adair and State 5 of Iowa, have invented certain new and useful Improvements in Hens' Nests; and I do hereby declare the following to be a full, clear, and exact description of the invention.

This invention has relation to improvements 10 in hens' nests.

The main object of the invention is to provide a hen-house containing a series of nests which will be cheap in construction and can be easily kept clean and ventilated, the partitions being so arranged that the compartments 15 may be readily made small or large at will and the supplemental or movable floor taken out and replaced after cleaning without removing any of the parts of the house.

20 With these ends in view I will now proceed to describe its construction and operation.

In the accompanying drawings, Figure 1 is a perspective view of my device. Fig. 2 is a longitudinal sectional view of the same, and 25 Fig. 3 is a perspective view of one of the partitions.

In carrying out my invention I employ a suitable frame, A', which is preferably of 30 rectangular elongated form. The frame consists of a stationary bottom, a', top B, and ends or side walls, b b. The top of this frame is provided on its under side with transverse grooves c, (there being but one shown in the drawings.) Secured to the respective corners 35 of the frame are vertical strips d, which are provided on their adjacent sides with longitudinal grooves d', which extend their entire length, the lower ends of the said strips being a sufficient distance above the stationary bottom a' for the insertion of the sliding or 40 removable floor-sections. Secured at the back of the frame to the top are vertical strips e, which are provided in their sides with grooves b', and their lower or free ends are on the 45 same horizontal plane as those of the corner-strips d, to also engage the upper surface of the supplemental or removable floor-sections, the said grooved portions of the strips extending laterally with relation to the partitions when the latter are in their normal position. In the present instance I have shown 50 but one strip e, but there may be any suitable number, according to the size of the house, and arranged in any desired space between the 55 corner-strips joining the grooves c in the top.

B' indicates the removable vertical partitions, having secured at their outer vertical edges strips f. These strips are secured a short distance above the upper ends of the said partitions, and are also provided with 60 lateral extensions having longitudinal vertical grooves similar to those of the other strips, and engage at their lower ends the upper surface of the supplemental floor-sections. Thus it will be seen that the vertically-grooved 65 strips at the front of the frame are made fast to the partitions, while those at the rear are secured to the top of the frame, having their lower ends a sufficient distance above the stationary floor for the insertion of the removable or supplemental floor.

C indicates the removable or supplemental floor-sections, which are arranged one for each nest or compartment in the house. These floor-sections are designed to slide above the 70 stationary bottom a', as before described, and, being longer than the width of the main frame, will extend over its longitudinal edges to serve as a perch or rest for the hens. The said floor-sections are prevented from vertical and lateral play or displacement by the engagement of the vertical corner-strips and the strips e and f. The extensions of the supplemental floor-sections also serve as a rest or support for the closing slats or strips 80 g, which may be provided with semicircular or other suitable openings for the admission of air and light to the house. The slats g are placed from above in the grooves of the vertical strips d, e, and f, to close the nests. 90

Having thus described my invention, what I claim as new, and desire to secure by Letters Patent, is—

The combination, with the frame A', constructed as described and provided with the 95 vertically-grooved corner-strips d, of the intermediate vertically-grooved strip, e, the top having a transverse groove arranged on its under side relatively at right angles to the said intermediate strip, e, the supplemental 100 floor-sections, a transverse partition provided on its front edge with a vertically-grooved strip, f, and the front and rear closing-slats, g, provided with ventilating-apertures, substantially as specified.

FRANCIS M. BROWN.
